UNITED STATES PATENT OFFICE.

WILLIAM G. PHILIPS, OF NEWPORT, DELAWARE.

DESIGN FOR AN ARM-CHAIR.

Specification forming part of Design No. 1,574, dated May 6, 1862.

To all whom it may concern:

Be it known that I, WILLIAM G. PHILIPS, of Newport, in the county of New Castle and State of Delaware, have invented or produced a new and original Design for an Arm-Chair; and I do hereby declare that the following is a full, clear, and exact description of the same, reference being had to the accompanying drawing, making a part of this specification, said drawing being a perspective view of a folding chair constructed according to my design.

The general character of the design is that of curves.

A A represent the front and B B the back legs of the chair. These legs are of circular form in their transverse section and curved longitudinally, and are connected by straight beaded rounds C D D. The upper parts of the legs are straight, the curves commencing about at the junction of the rounds D D.

E E represent the side rails of the seat and back of the chair. These rails at their lower parts are also of circular form in their trans-

verse section, and are curved longitudinally, so that one portion will be nearly or quite at right angles to the other portion, as shown clearly in the drawing. The front ends of the rails E are beaded, as shown at a, and the upper back parts of the rails are of elliptical form in their transverse section.

F F represent the arms of the chair, which are connected to the rails E E and are curved longitudinally in cymatium form, but are of elliptical form in their transverse section.

The chair as a whole, it will be seen, is a combination of curves, the rounds C D D alone excepted. G is the seat, and H the back.

Having thus described my invention, what I claim as new, and desire to secure by Letters Patent, is—

The general configuration of the parts, as herein shown and described, to form a new and original design for an arm-chair.

WM. G. PHILIPS.
